G. RIMMER

COAL CUTTING MACHINE

Filed Jan. 10, 1925

Fig. 1.

UNITED STATES PATENT OFFICE.

GILBERT RIMMER, OF RADFORD, ENGLAND, ASSIGNOR TO SULLIVAN MACHINERY COMPANY, OF CHICAGO, ILLINOIS.

COAL-CUTTING MACHINE.

Application filed January 10, 1925. Serial No. 1,687.

To all whom it may concern:

Be it known that I, GILBERT RIMMER, a subject of the King of England, residing in Radford, Nottingham, England, have invented certain new and useful Improvements in Coal-Cutting Machines, of which the following is a specification.

This invention consists in improvements in or relating to coal-cutting machines wherein there is a pivoted jib which is capable of being slewed about its pivot and round the margin of which is an endless chain termed the "cutter-chain" armed with cutting tools or picks and travelling in the plane of the jib.

It is customary to utilize the haulage-chain, which is generally an ordinary loose link chain, to slew the jib and hitherto difficulty has been experienced from the fact that the haulage-chain should it become slack, is liable to sag and foul the fast moving cutter-chain.

One means for overcoming this drawback is described in prior British Patent No. 25 196,004 and comprises a bridging connector serving as a continuation of the end of the haulage or other chain which is to be connected to the jib for the purpose of slewling it. The present invention is designed to improve such bridging connector and is applied to that type of such device comprising two or more links pivotally connected to one another end-to-end with the axis of pivoting transverse to the plane in which 35 the cutter-chain moves.

According to the present invention the connector is combined with one or more rolling or anti-friction members associated therewith to afford a bearing surface or 40 bearing surfaces between said connector and an adjacent part of the coal-cutting machine. When rollers or like devices are employed each of them is preferably rotatably mounted in the connector to rotate about an 45 axis which is parallel with or coincident with the axis of hinging between the links of the connector.

When the jib is employed in arc-cutting work, it must generally be slewed through 50 an angle of rather more than 180° several times a day. In ordinary longwall work it is slewed through approximately 90° only. It is necessary, however, for the machine to be so designed that the jib can be slewed 55 through the larger angle and consequently

the bridging connector or as it is sometimes called the sumping hook attachment, has to be of considerable length and greater than would be necessary if only the smaller angle had to be accommodated. During the slew- 60 ing, the chain and the connector at its end have usually been, in one position of the jib, lapped round the end or head-member of the coal-cutting machine, and it is found of considerable advantage to provide the means 65 according to the present invention whereby the friction between the connector or sumping hook and the adjacent wall of the coal-cutting machine is considerably reduced.

In order that the invention may be more clearly understood, one preferred form of the invention will now be described in detail by way of example only, with the aid of the accompanying drawings, in which—

Figure 1 is a plan view of a portion of the 75 jib and the connector, and

Figure 2 is an elevation of the parts illustrated in Figure 1 with the connector removed for the sake of clearness.

Like reference numerals indicate like parts 80 in both figures of the drawings.

An inboard portion of the main suspension member for the jib, or back-hanger as it is sometimes termed, is represented at 1 and is adapted to be slewed, in the end or head of the coal-cutting machine, about the axis of an orifice 2. The outer contour of the end or head is indicated in chain lines at 3.

Mounted on the part 1 is a bracket 4 which 90 is secured to the part 1 in any preferred manner and is formed with an upstanding wall 5 to which is secured, by means of bolts 6 a bracket 7.

The connector above referred to is in the 95 form of a link-chain, the links of which are indicated by the reference numeral 8, made up of a number of links pivoted together end to end by pivot-pins 9. On the pivot-pins 9 are mounted rollers or wheels 10 each 100 of which extends laterally beyond the sides of the chain so that the peripheries of the rollers or wheels only engage with the adjacent surface of that wall or part of the cutting-machine indicated by the reference 105 numeral 3. The surfaces of the links are thus maintained free from engagement with the part 3.

On the bracket 7 at each end are pairs of 110 spaced ears or lugs 11 each pair being pro-

vided with co-axial apertures 12. The ears or lugs 11 at each end are spaced apart sufficiently to receive between them the end links of the connector and the latter is secured to the bracket 7 by a pin 13 passing through the orifices in the end links of the chain and through the apertures 12 in the lugs 11. In Figure 1 the connector is illustrated as secured to one pair of ears or lugs 11 but it will be understood that it may be removed from that end of the bracket 7 and secured between the lugs 11 at the other end thereof.

It will be seen therefore that when a long connector or sumping hook consisting of a comparatively large number of links is employed it is the connector itself which is mainly or wholly lapped around the head 3 of the cutting machine so that when the anti-friction devices, such as the wheels 10, are provided according to the present invention, the bulk of the friction-loss above referred to is eliminated.

In the specific embodiment described the connector is sufficiently inflexible in a direction towards the jib as to prevent it sagging in its own length so far towards the cutter-chain as to permit fouling with the latter. Its length is so chosen that both the connector and the haulage-chain, which will be engaged by the hook 14 at the end of the connector, will be kept clear of the cutter-chain if, for example, any tilting movement of the connector towards the jib is permitted by the operative connection between the two parts.

The above described embodiment is capable of many modifications in detail without departing from the spirit of the invention, and the invention includes all such modifications.

I claim:

1. For use in conjunction with a mining machine having a frame having an arcuate guiding surface and a cutter bar pivoted on

an axis in substantially the same line with the axis of said arcuate surface, a flexible tension element having means for connecting it in fixed relation to the bar to apply a swinging force to the latter, said element being adapted to flex only in planes parallel to the plane of bar swing and having rolling means associated therewith and adapted to engage said guiding surface as said element is flexed around the latter.

2. For use in conjunction with a mining machine having a frame having an arcuate guiding surface and a cutter bar pivoted on an axis in substantially the same line with the axis of said arcuate surface, a flexible tension element having means for connecting it in fixed relation to the bar to apply a swinging force to the latter, said element being adapted to flex only in planes parallel to the planes of bar swing and comprising a plurality of links hinged together on axes perpendicular to the plane of bar swing and rolling means rotatable on axes substantially perpendicular to the plane of bar swing and adapted to engage said guiding surface as said element is flexed around the latter.

3. For use in conjunction with a mining machine having a frame having an arcuate guiding surface and a cutter bar pivoted on an axis in substantially the same line with the axis of said arcuate surface, a flexible tension element having means for connecting it in fixed relation to the bar to apply a swinging force to the latter, said element being adapted to flex only in planes parallel to the plane of bar swing and comprising a plurality of links hinged together on axes perpendicular to the plane of bar swing and having rolling means rotatable on axes coincident with said axes of hinging, said rolling means being adapted to engage said guiding surface as said element is flexed around the latter.

In testimony whereof I affix my signature.
GILBERT RIMMER.
